UNITED STATES PATENT OFFICE.

LOUIS E. HACHERELLE, OF PEORIA, ILLINOIS.

DESIGN FOR A DRESS-FORM.

SPECIFICATION forming part of **Design No. 26,690**, dated February 23, 1897.

Application filed April 20, 1896. Serial No. 588,391. Term of patent 3½ years.

To all whom it may concern:

Be it known that I, LOUIS E. HACHERELLE, a citizen of the United States, residing at Peoria, in the county of Peoria and State of Illinois, 5 have produced a new and original Design for Dress-Forms; and I do hereby declare that the following is a full, clear, and exact description of the invention, which will enable others skilled in the art to which it appertains to make and use the same.

My invention relates to a new and original design for dress-forms as represented in the accompanying drawings, in which—

Figure 1 is a front view of the dress-form, 15 and Fig. 2 is a vertical section on the line 2—2, Fig. 1.

In the drawings, 1 represents the form, which is symmetrical as to two sides and is divided by a central line 2. It has an upper 20 concave curve 3, concave curves 4 at the sides, and ogee curves 5, extending downwardly from the curves 5 to the bottom. Ex-

tending upwardly from the bottom are pattern-lines 7, and at or near the upper ends of said lines is on each side a group 8 of substantially parallel pattern-lines 9. Each group has an upper edge or border 10, substantially parallel with the edge 11 of the form, an edge 12, substantially parallel with the curve 4, and a convex curve 13, extending first downwardly in an oval or elliptical form and then upward adjacent to the central line 2 and meeting the terminus of the edge 10.

The contour in vertical section, as shown in Fig. 2, is of an ogee curvature.

I claim—

The design for a dress-form substantially as shown.

In testimony whereof I affix my signature in presence of two witnesses.

LOUIS E. HACHERELLE.
